PERLEY R. GLASS, OF WAYLAND, MASSACHUSETTS, ASSIGNOR TO P. R. GLASS COMPANY, OF BOSTON, MASSACHUSETTS, A CORPORATION OF MASSACHUSETTS.

FOLDING MACHINE.

1,406,371.

Specification of Letters Patent. Patented Feb. 14, 1922.

Application filed June 24, 1920. Serial No. 391,486.

To all whom it may concern:

Be it known that I, PERLEY R. GLASS, a citizen of the United States, residing at Wayland, in the county of Middlesex and 5 State of Massachusetts, have invented certain Improvements in Folding Machines, of which the following description, in connection with the accompanying drawings, is a specification, like reference characters on the 10 drawings indicating like parts in the several figures.

This invention relates to folding machines and is herein described as embodied in a machine for folding the margin of a piece of 15 leather or similar sheet material which is to be incorporated in boots and shoes.

In the manufacture of boots and shoes it is customary to fold the margins of certain pieces of upper material such as vamps and 20 tips in order to finish those edges which are exposed in the completed shoe. Various types of machines are used to carry out this folding operation, but all of them, so far as I am aware, comprise some sort of a folder 25 for forming the fold and a hammer or similar member for pressing the fold. Commonly a machine of the intermittent feed type is employed whereby the fold is progressively formed and pressed. Such machines are usually provided with a hammer 30 or fold presser which is oscillated about an axis lying substantially parallel to the line of feed of the work, the hammer thus moving in a curved path the plane of which is 35 transverse to that line. With such a construction the flat operative face of the hammer will be parallel with the flat surface of the anvil or other member which supports the work only in one position of the hammer.

40 It is desirable that this parallel relation should occur when the hammer exerts pressure upon the work so that the blow of the hammer may fall squarely upon the folded margin; but with former constructions this

45 condition obtains only with a piece of work of a predetermined thickness. If the work is thicker or thinner than the predetermined thickness, the operative face of the hammer will be inclined slightly in one direction or 50 the other to the plane of the work support at the time the blow is struck. It has been proposed to use a hammer pivoted about an axis which lies substantially in the plane of the surface of the work support and to permit yielding movement of the hammer transversely of its pressing face and of the pivot 55

during the application of the pressure to the fold. Such a construction, however, is objectionable because the face of the hammer first strikes the edge of the fold and then 60 rocks about the edge, the result being that too much pressure is applied to the edge. In the discussion given above it has been assumed that the folded margin is of a uniform thickness throughout. It sometimes 65 happens that this is not the case, the edge being slightly thinner or thicker than the body of the folded margin. In such case the face of the hammer during the pressing of the fold should be inclined slightly to the 70 plane of the work support.

In order to provide for these and similar conditions, one of the members, the hammer and anvil, between which the fold is pressed is so constructed and arranged that it will 75 accommodate itself to the particular folded margin which is being operated upon whether that margin be thick or thin, of uniform or non-uniform thickness and will accommodate itself immediately upon contact 80 with the work before any appreciable pressure is applied to the fold. In the illustrative machine the hammer is provided with a swiveled striking plate, the axis about which the plate is swiveled being substantially 85 parallel to the line of the fold and lying above the folded margin when the hammer is in operative relation to the work. With such a construction the striking plate, as soon as it contacts with the work, assumes 90 a position such that the pressure which it applies is exerted squarely upon the folded margin.

This and other features of the invention, including certain details of construction and 95 combinations of parts, will be described as embodied in an illustrative machine and pointed out in the appended claims.

Referring now to the accompanying drawings,

100 Fig. 1 is a perspective view of a portion of a machine in which the present invention is embodied, the view showing more particularly the parts of the machine which engage the work;

105 Fig. 2 is another perspective, but from a different angle, showing more particularly the mounting of the feed slide and the hammer, and

110 Fig. 3 is a section through the hammer, the anvil, and a piece of work.

The illustrative machine, except for cer-

tain features hereinafter to be noted, is like the machine of Patent No. 1,281,555, granted Oct. 15, 1918, upon an application filed in my name; and before pointing out in detail the features of the present invention, the general construction and mode of operation of the machine will be briefly described, making use of the same reference numerals which appear in the patent.

10 Referring first to Fig. 1, the work, the margin of which is to be folded, is fed over a work table 12 by means of a hammer 150 and anvil 104 which intermittently grip the work and feed it forward. The edge of the 15 work runs against a preliminary turning member or plow 30 and underneath a pivoted gage member 32, the margin at that time being turned up a little less than 90°. The turned-up margin may then be acted 20 upon if desired by a snipping knife 40. The snipping knife is normally inoperative but may be rendered operative at any time by depressing a treadle (not shown). The snipping knife is thrown into operation only 25 when a concavely curved margin is encountered, the purpose being to facilitate the folding of such a margin. The work, after passing the knife, whether it is snipped or not, is next bent over the edge of a creaser 30 90 by a folding finger 80 which rises intermittently, this bending of the margin serving to form the fold. The fold, thus formed, is next gripped between the hammer and anvil to press or complete it; and then the 35 hammer and anvil, as stated above, move rearwardly to impart an intermittent feed movement to the work.

The knife 40 is mounted at the end of a bent lever 42 which is pivoted to a stud 44 40 carried by an overhanging arm 13 which is part of the frame of the machine; and a link 46 connects the bent lever with treadle controlled mechanism not shown herein but fully shown and described in the prior patent referred to above. The creaser 90 is carried by a block 92 which in turn is pivotally mounted on a bar 36 also carried by the overhanging arm 13. For the details of the mounting of the creaser reference is made 50 to the patent.

The mounting of the hammer and the anvil is like that of the machine of the patent but will be described a little more in detail since the improvement of the present invention has to do with these members. Mounted to slide back and forth in the line of feed is a slide 120 (see Fig. 2) which has fast to it the anvil 104 and a rod 122 upon which the hammer 150 oscillates. The slide 60 120 is reciprocated by a bell crank lever 166 the upright arm of which carries a swivel block 164 and the horizontal arm of which is pivoted to the upper end of a link 170.

The swivel block 164 lies between ears 162 formed on the under side of the slide 120, so 65 that oscillation of the bell crank lever 166 causes reciprocation of the slide. In order to cause such oscillation, the lower end of the link 170 has pivoted to it a swivel block 172 which fits in a slot in a cam lever 174, 70 said lever being pivoted at one end on a rod 9 and having at its other end a fork which embraces an eccentric (not shown) on the driving shaft 16. Treadle controlled means (not shown) are provided for shifting the 75 block 172 toward and from the rod 9 to decrease or increase the throw of the bell crank lever 166 and thus to shorten or lengthen the extent of the intermittent feed movements, it being understood that the 80 hammer 150 and anvil 104 move back and forth with the slide 120.

In order to oscillate the hammer, the following construction is provided. The hammer is loosely mounted on the rod 122 and 85 has a depending tail which carries a hollow boss 150 inside of which is slidably mounted a spring-pressed plunger 153. An actuator 152, also loosely mounted on the rod 122, has depending ears. One of these is engaged 90 by the spring-pressed plunger 153; the other carries a screw which engages the back of the tail of the hammer. It is evident, then, that the angular position of the hammer with respect to the rod 122 depends upon 95 the angular position of the actuator 152 and that oscillation of the actuator will cause oscillation of the hammer. The purpose of the spring plunger 153 is to ensure that the blow struck by the hammer shall be a yielding one. Oscillation of the actuator 152 is caused through suitable linkage indicated at 100 157 which is pivotally connected with a cam arm 160 operated by an eccentric 18. No further description of the general construction of the old machine will be given, since the details of its construction form no part of the present invention. It will be understood, however, that the machine operates progressively first to form and then to hammer or press the fold. 105

In prior folding machines the operative face of the hammer has commonly been rigid or of the objectionable yielding construction, which has been referred to, with 115 the result, for example, that, with the hammer constructed or adjusted to operate satisfactorily upon thin work, if a thick piece of work is presented to the machine, the hammer will not strike the fold squarely. In 120 order to provide for this and similar conditions the head of the hammer 150 is provided with a swiveled striking plate 201. This striking plate has formed upon its upper side a rounded rib 203 which fits in a 125 correspondingly shaped transverse groove in

the head of the hammer; and in order to prevent the striking plate from sliding along the groove, the rounded rib 203 and the hammer head have grooves formed in them which register when the parts are properly assembled; and, extending through these grooves, is a locking member in the form of a comparatively weak leaf spring 205 fastened to the hammer head by a screw 10 207. It will be noted that the axis of the rounded rib 203 is substantially parallel to the line of feed of the work; and that the operative face of the striking plate 201 will therefore accommodate its position in accordance with the folded margin immediately upon contact with the work so as to strike the work squarely whether said margin be thick or thin and whether it be of uniform or non-uniform thickness. By 15 20 mounting the striking plate in the head of the hammer as described, the axis about which the plate is pivoted lies above the folded margin when the hammer is in operative position, and the striking plate is 25 thereby permitted to tilt either toward or from the edge as may be required. As has been stated, the leaf spring 205 is comparatively weak, being just strong enough to maintain the striking plate normally in the 30 position relative to the hammer shown in Fig. 3 so that, as the hammer is oscillated, the plate will not rattle. It is not strong enough to offer any appreciable resistance to angular movement of the plate; and consequently the plate is substantially free to move in either direction about its axis with the result that the moment the plate contacts with the work and before any appreciable pressure is applied, the plate accommodates its position to the particular work 35 40 being operated upon. As a consequence, there is no objectionable rocking of the plate in a manner to exert more pressure upon one portion of the fold than upon another. 45 Although the invention has been set forth as embodied in a particular machine in which, for example, the hammer acts to feed the work as well as to press the fold, it should be understood that the invention is 50 not limited in the scope of its application to the particular machine which has been shown and described.

Having thus described my invention, what I claim as new and desire to secure by Letters Patent of the United States is:

1. A machine of the class described, having in combination, a support for a piece of material, means for forming a fold in the margin thereof, and co-operating members 60 for pressing the fold, one of said members being pivoted and so easily movable in two directions about an axis substantially parallel to the line of the fold that, immediately upon contact with the fold and before any appreciable pressure is applied, the pivoted

member will accommodate its position to the shape of the fold.

2. A machine of the class described, having in combination, a support for a piece of material, means for forming a fold in the margin thereof, and co-operating members for pressing the fold, one of said members being pivoted about an axis located inside the edge of the fold whereby, immediately upon contact with the fold and before any appreciable pressure is applied, the pivoted member will accommodate its position to the shape of the fold. 70 75

3. A machine of the class described, having in combination, a support for a piece of material, means for forming a fold in the margin thereof, and a co-operating hammer and anvil members for pressing the fold, one of said members being pivoted about an axis which, when the members are in pressing relation, lies in a plane substantially perpendicular to the material and inside the edge thereof. 80 85

4. A machine of the class described, having in combination, a support over which the work to be folded is fed, a co-operating creaser and folder for forming the fold, and a co-operating hammer and anvil for pressing the fold, one of said last-named members having a work-contacting member 90 adapted to rock in either direction as may be required about an axis which is substantially parallel to the line of the fold. 95

5. A machine of the class described, having in combination, a support for a piece of flexible material, means for forming a fold in the margin thereof, and a combined hammer and feed member for pressing the fold and for feeding the material, said hammer including a swiveled striking plate mounted 100 105 in the head thereof.

6. A machine of the class described, having in combination, a support over which the material to be folded is fed, means for progressively forming a fold in the margin 110 of the material, and means for pressing the fold, said last-named means comprising a hammer having a rounded groove in the head thereof and a striking plate having a rounded rib received in the groove. 115

7. A machine of the class described, having in combination, a support over which the material to be folded is fed, means for progressively forming a fold in the margin of the material, and means for pressing the fold, said last-named means comprising a reciprocating hammer so constructed and mounted that its head is located at all times above the level of the support, and a striking plate pivoted to the head and as freely 120 125 movable in one direction as in the other about the axis of the pivot.

8. A machine of the class described, having in combination, a support over which the material to be folded is fed, means for pro- 130

gressively forming a fold in the margin of the material, and means for pressing the fold, said last-named means comprising a hammer having a rounded groove therein running substantially parallel to the line of feed of the work, a striking plate having a rounded rib received in the groove, there being a transverse groove in the rib, and a leaf spring fast at one end to the hammer and extending into the transverse groove.

9. A machine of the class described, having in combination, a support over which the

material to be folded is fed, means for progressively forming a fold in the margin of the material, and means for pressing the fold, said last-named means comprising a hammer and a striking plate pivoted in the head of the hammer about an axis which is spaced from the ends of the plate to permit either end of the plate to rise while the other descends.

In testimony whereof I have signed my name to this specification.

PERLEY R. GLASS.
